Application March 1, 1937, Serial No. 128,330

6 Claims. (Cl. 60—16)

This invention relates to internal combustion engines, and more particularly to engine starting mechanism of fluid-pressure type having particular application to engines of the Diesel type.

- 5 It is the general practice particularly in connection with the larger engines of Diesel type, to provide either an electric starting system or a fluid-pressure starting system for such engines, the choice of the system to be utilized being in many 10 instances determined by the availability at the intended location of the engine, of a suitable source of electric power or of fluid under pressure, such as compressed air. In some engine installations, it is desirable and preferred to provide both 15 types of starting systems, to be utilized as occasion demands, either separately or in combination to effect starting of the engine. Accordingly, it is an object of the present invention to provide an improved air starting mechanism of unit type, 20 which is readily applicable to multi-cylinder engines, the number of units employed being determined by the number of engine cylinders, and further, in which the units are adapted for application to engines which may or may not be 25 already equipped with electric starters, the operative assembly of the units to an engine being made without altering the engine organization.

Another object is to provide an air starting mechanism of unit type which may be readily applied to internal combustion engines, for use either alone or in conjunction with an electrical starting system, the units being adapted for ready removal without disturbing or otherwise affecting the engine organization.

35 A further object is attained in the provision of air starting units which, when more than one unit is required, may be coupled in a predetermined manner, so as to attain a delivery of starting air to the cylinders in a sequence which corresponds to the firing order of the cylinders.

40 Further objects and advantages will appear from the following description, and from the drawings, in which:

Fig. 1 is an assembly elevation of a part of an 45 internal combustion engine, illustrating the application thereto, of a unit type of air starting mechanism embodying the improvements of this invention; Fig. 2 is an enlarged, fragmentary end elevation of the engine, as taken along line 2—2 in Fig. 1 and showing in section, a part of one 50 of the starting units, the view also showing portions of the engine broken away to illustrate the application of the starting mechanism thereto; Fig. 3 is an enlarged sectional elevation of a portion 55 of one of the units, as taken along line 3—3

in Fig. 1; Fig. 4 is an enlarged, fragmentary front elevation of a starting unit, with a portion thereof broken away to show certain operating elements for the unit, as viewed from line 4—4 in Fig. 2, and Fig. 5 is an enlarged section through a starting unit, as viewed from line 5—5 in Fig. 1.

Referring now to the drawings by suitable characters of reference, the air starting mechanism embodying the improvements of this invention, is associated in a novel manner with a multi-cylinder, internal combustion engine denoted, generally, by the numeral 5. The engine illustrated in the present example is, by preference, of the 4-cycle Diesel type, those parts of the engine shown including an engine housing 6, crankcase 7, a portion of the engine frame 8, cylinder organizations 10, 11, 12, 13 and 14, a fuel injection device 16 for each of the cylinders, a fuel supply pump 17 for each of the injection devices 16, a conduit 18 connecting each pump with its respective injection device, and an engine cam shaft 19 (Fig. 2). The shaft 19 may represent the main cam shaft carrying the scavenging air and exhaust valve operating cams for each cylinder, such as the cams 20 and 22 respectively, as shown in Fig. 4. In the present example and as will later appear, the exhaust cams 22 are utilized as operating means for the engine starting units now to be described, although it is to be understood that the air valve operating cams 20 may be employed for this purpose, instead of the cams 22.

The crankcase portion 7 of the engine housing 6, on the air inlet and exhaust valve side of the engine organization, is furnished with a number of openings providing access to the cam shaft 35 bearings and other parts of the engine in the crankcase zone, three such openings being shown in the present example, at 23, 24 and 25. These openings are normally closed by suitable cover plates 26, 27 and 28, respectively, each cover being secured in place by suitable bolts 29 and a hand-operated star-wheel member 30 threadedly engaging a stud 32 carried by the portion 8 of the engine frame. A suitable gasket 33 may be provided between the cover and the crankcase to 45 seal the crankcase opening. Each cover plate is provided with an opening 34 in the lower side thereof (Fig. 2), serving to permit inspection of the cam shaft and bearings without removing the cover plate. Opening 34 is normally closed by a 50 cover 35 which may be secured in assembly to the cover plate, by suitable bolts 36. A sealing gasket 37 may be provided for the cover 35, as shown in Fig. 2.

As before noted, the principal object of the 55

present invention is to provide air-starting apparatus of unit type, which may be readily applied to multi-cylinder engines through the use of one or more of the units, the number of units employed being determined by the number of engine cylinders to be supplied with starting air. The air-start units may be applied to engines already equipped with electric starting apparatus, and may be utilized either alone or in conjunction with the electric starter, for starting the engine. In the present example, apparatus forming a starting unit is carried by each of the cover plates 26, 27 and 28, with certain elements of such apparatus preferably formed as an integral part of the cover plate. As each cover plate and the unit starting apparatus carried thereby are substantially identical, only one thereof will be described in detail and like reference numerals will apply to the similar parts of the other units.

20 The cover plate 26 carrying starting apparatus forming a unit of the system, is substantially rectangular in form and is concave in its lateral extent, as shown in section in Figs. 2 and 3. Extending longitudinally of the upper portion 38 of the cover plate, and between the ends 39 and 40 thereof, is a conduit structure 42, the conduit being formed as an integral part of the plate on the concave side thereof. The conduit is divided by a central partition 43 to form separate chambers 44 and 45, these chambers being provided near the end 39 of the plate (Fig. 5), with an inlet passage 46 and 47 respectively, extending laterally through the cover plate and through a boss 48 formed on the plate. An inlet fitting 49 is secured by bolts 50, to the boss 48, and is provided with separate inlet passages 52 and 53 in communication respectively, with the inlet passages 46 and 47. Passage 52 in the fitting terminates in a conduit connecting projection or nipple 54, to which is connected an air supply conduit 55 having a control valve 56 associated therewith. Similarly, fitting passage 53 terminates in a nipple 57 to which is connected a second air supply conduit 58, also provided with a control valve, such as 59. In the present example, each valve is adapted for manual control through a lever 60. The conduits 55 and 58 may extend to any suitable source of air under pressure (not shown). The chambers 44 and 45 are provided near the end 40 of the cover plate, with outlet passages 62 and 63 respectively, extending laterally through the cover plate, these passages being shown in dotted lines in Fig. 1. A fitting 64 having separate, parallel passages 65 and 66 therein, is secured on one end 67 to the cover plate 26 as by bolts 68, and on its opposite end 69 to the end portion 39 of cover plate 27 as by bolts 70. The arrangement of the fitting is such as to provide, through passage 65 therein, communication between the outlet passage 62 of chamber 44 and the inlet passage 46 of chamber 44 in cover plate 27, and through passage 66, communication between the outlet passage 63 of chamber 45 in cover plate 26 and the inlet passage 47 of chamber 45 in cover plate 27. A similar fitting element 72 connects the chambers of cover plate 27 with those in plate 28. The fitting 72 however is formed to provide a crossed-connection, so that chamber 44 in plate 27 is in communication with chamber 45 in plate 27 and chamber 44 in plate 28. The arrangement of the inlet and outlet openings in the several cover plates, the relative disposition of these cover plates in assembly and the form of the fittings 64 and 72 are such that these

fittings may be readily interchanged to secure straight or crossed connections, to attain a predetermined flow of air between units according to the desired order of air delivery to the engine cylinders, as will be later described.

Formed as a part of the conduit structure 42 near the end 39 of cover plate 26, is a valve structure 73 which includes a casing 74 (Fig. 2) extending laterally through the conduit structure and outwardly thereof, as at 75. A casing bore 10 76 extends to the outer face of the cover plate and is normally closed by a screw plug 78. Seated within the bore 76 near the casing end 75 is a bushing 79 which is centrally apertured to receive the stem 82 of a valve 82, the bushing serving as 15 a bearing and guide for the valve stem. The valve casing is formed with an annular flange within the casing bore 76, which provides a seat for the valve 82. A spring 85 sleeved about the valve stem and arranged between the valve 82 20 and the bushing 79, serves to urge the valve to open position, with the valve 82 abutting a stop element 87 carried by the screw plug 78.

The chamber 44 communicates with the bore 16 in the valve casing through a port 88 in the 25 casing located adjacent the valve 82 and on the valve head side. Extending upwardly from the end portion 75 of the valve casing, is a conduit section 89, the conduit on its lower end being in communication with the valve bore 76 through a 30 port located rearwardly of the valve. Thus the valve 82 serves to control the flow of fluid from chamber 44 to conduit 89. The conduit 89 extends to a bossed portion 92 formed integrally with the conduit and with the external upper edge 35 portion 38 of the cover plate 26. A conduit 94 having one end secured to the boss 92, as by the coupling element 96, forms a continuation of the conduit 89, and extends to a valve structure 93 secured in any suitable manner to the cylinder 40 head 100 of cylinder organization 10. Valve 98 which may be of any suitable type permitting passage of fluid therethrough in one direction only, communicates with a passage 102 in the cylinder head leading to the combustion space 103 within 45 the cylinder structure. The function of this valve is to permit flow of starting air to the cylinder without a return of any part of such air to the air supply system. The valve also effectively prevents a flow of fuel and combustion gases from the cylinder into the air start units, during operation of the engine. The details of the valve structure 98 need not be given, as such, per se, forms no part of the present invention.

Interposed between the end 104 of valve stem 55 89 and one of the cams 22 on engine camshaft 19, is a cam-operated, valve-actuating device 105. The device 105 is comprised, by preference, of a member 106 which is freely pivoted, by means of a pair of arms 107 upon a shaft 108 suitably supported by the engine frame 8. The member 106 carries a roller 109 near one end thereof, the roller being in register with, and engageable by the cam 22 (Fig. 4). The member 106 also supports an adjustable abutment which in the present example may comprise a screw 113 threadedly engaging any one of a number of threaded apertures 114 in a depending portion 115 of the member 106 with the screw retained in adjusted position by a suitable lock nut. The abutment normally engages the end of valve stem 89 and is urged into engagement therewith by a spring 117 arranged between a projection 118 on the portion 115 of member 106 and a spring anchorage 119 on the engine frame. The arrangement of the piv- 75

oted member 106 and spring 117 is such that when the spring is unopposed by any counter-force, it will maintain the member 106 out of position for engagement of the cam 22 with the roller 109. The provision of the threaded apertures 114 for receiving the screw 113 is made so that the screw may be properly aligned with the end of its associated valve stem 80, while the axial adjustment of the screw serves to permit axial positioning of the screw relative to the valve stem, so that the valve may be properly operated by the cam 22. Also, the latter adjustment may be utilized to effect an individual regulation of the time of opening of each valve, as will be readily observed from an inspection of Fig. 2.

A valve structure 125 similar to the valve structure 73 and its associated parts above described, is disposed near the end 40 of cover plate 26, and is in communication with the chamber 45 through a port 126 (Fig. 1). Extending from the outlet connection 127 of valve 125 is a conduit 128 leading to a one-way valve 129, similar to valve 98, in the cylinder head 130 of cylinder 11. The plate 26 carrying the two valve structures 73 and 125 and their respective cylinder-connecting conduits 94 and 128, forms a unit air-starting device which is duplicated on cover plates 27 and 28, only a part of the unit of plate 28 however, being shown in the present example. Thus valve 73 on plate 27 is associated with a one-way valve 98 in cylinder 12 through a conduit 94, while the valve 125 on plate 27 is associated with a like one-way valve 129 in cylinder 13 through conduit 128. Similarly with the valves 73 and 125 (not shown) on plate 28. Associated with each of the air start valves of course, is a cam-actuated, valve-operating device such as the member 106 and its associated parts, as above described.

For a two cylinder engine, only one starting unit such as that formed by plate 26, will be required, while for engines of a greater number of cylinders, a correspondingly greater number of units will be required. The interconnection of the units, where more than one is employed, is made through straight fittings such as the fitting 64, or crossed fittings such as the fitting 72.

The operation of the system is such that upon opening the air supply valve 56, air under pressure will be delivered to the chamber 44 in plate 26 and will flow into the valve casing 74 through port 88, as shown by an arrow. Initially, the valves 73 and 125 in each of the units are in open position, under the influence of the valve springs 85, so that considering the valve structure 73 in plate 26, as the compressed air enters valve casing 74, the air will cause the valve 82 to close. With the closing of the valve, the valve stem 80 will abut screw 113 and move the rocker structure identified with member 106 into a position so that the cam 22 may periodically contact the roller 109, thus effecting a periodic opening of the valve 82 against the pressure of the air. Opening of valve 82 by cam 22 is aided by the valve spring 85 and also by the spring 117. Opening of the valve 82 permits compressed air to flow by the valve and through the conduits 89 and 94 to the one-way valve 98, from whence the air is delivered to the engine cylinder chamber 103 in cylinder 10 through the passage 102.

Air delivered to chamber 44 in plate 26 will also flow through this chamber and to the similar chamber 44 in plate 27, through the passage 65 in fitting 64. Part of the air thus delivered

to chamber 44 in plate 27 will flow to valve 73 therein, as shown by the arrow 136 (Fig. 1), and will close this valve, unless it is held open by its actuating cam 22, as will be later described. The remainder of the air will continue through the chamber to the chamber 45 in plate 28, through the crossed-fitting 72, and will be delivered to the valve 125 (not shown) in that plate. Thus for example, with the valves in an open position, compressed air will be delivered to cylinders 10, 10 12 and the last cylinder (not shown) supplied from valve 125 in unit 28, assuming the engine 10 of Fig. 1 to be a 6-cylinder engine, as only five cylinders are shown.

Opening the other air supply valve 59 will effect a delivery of compressed air to chamber 45 in plate 26, chamber 45 in plate 27 through the passage 66 in fitting 64, and chamber 44 in plate 28 through the crossed fitting 72. In this case, air will be available for passage through valves 125 in plates 26 and 27, and valve 73 in plate 28, when these valves are opened. Thus with these valves in an open position, for example, compressed air will be delivered to the cylinders 11, 13 and 14.

It will now appear that the engine cylinders are, in effect, organized into two groups, the starting air for one of the groups being under the control of main valve 56, and the starting air for the other group being under the control of main valve 59. It is highly desirable that the particular cylinders making up each group be selected with regard to the firing order of the engine. In a six cylinder engine whose firing order is, for example, 1-4-6-2-3-5, cylinders 1, 6, 3 should preferably be identified with one of the main air valves, and cylinders 4, 2, 5 with the other main air valve. Thus when the air supply to one of the groups is cut off by the main air valve for that group, the power impulses occurring in the cylinders of the other group are evenly distributed with respect to the normal firing order of the engine, and the "balancing" of the power strokes is not disturbed. It will appear further that this balanced grouping of the cylinders can be attained by a proper selection of the type of fitting used for connecting the conduits of adjacent cover plates. Where, as in the present example, the cover plates and their associated air-starting means are standard for engines having two, four, six or more cylinders, each having a firing order peculiar thereto, the provision of straight or cross fittings for the aforementioned purpose is especially advantageous.

In the present example, the exhaust cams 22 are utilized to operate the air start valves, and since these cams are angularly spaced on cam shaft 19 in accordance with the desired firing order of the cylinders, the cams may effect an opening of the air start valves in the firing order. In starting the engine, at least one of the cams 22 must be initially in position to open its associated air start valve, so as to permit a flow of compressed air to the cylinder fed through such valve, for initiating starting of the engine. The compressed air delivered to this first cylinder will start the engine so as to rotate the cam shaft 19, and this in turn will effect through cams 22 on the cam shaft, subsequent opening of the other air start valves to deliver compressed air to the cylinders, preferably in the cylinder firing order. Each air start valve, of course, will be opened only when its cam 22 has actuated member 106, through contact with roller 109 on such member, 75

- to effect an opening of the valve in the manner heretofore described. The delivery of compressed air to the cylinders may be continued until the engine starts firing or until the engine 5 is in operation under its own power, at which time, the air supply valves 56 and 59 may be closed. Closing of the valves 56 and 59 will effect an immediate reduction in the pressure of the air in the chambers and passages of the 10 starting units, so that all the air start valves may open under the action of the valve springs 85 and as a result of the springs 117 pivotally displacing the members 106 out of position for engagement of the rollers 109 by the cams 22. 15
15. Thus during normal power operation of the engine, the air start valves will be in open position; and the members 106 and rollers 109 will be out of operative contact with the exhaust cams 22, the latter provision being effected to 20 prevent wear of the parts which would otherwise occur should the members 106 and rollers 109 be left in air-start position, as will be readily understood.

It is desired in the present example to point out 25 a preferred manner of utilizing the air start units for starting the engine. Accordingly, the engine may be started by first opening both air supply valves 56 and 59, for delivery of compressed air to all the cylinders, say in the firing order. Then, 30 after the engine has turned over one or more times, one of the supply valves is closed, leaving the other open to supply starting air to half the number of cylinders. The remaining cylinders may then be fired more quickly, since the cutting 35 off of starting air to these cylinders early in the starting operation has prevented chilling thereof through repeated expansion of the air in the cylinders on the expansion stroke of each piston. Thus, by closing supply valve 59 and leaving supply 40 valve 56 open, starting air will be delivered to cylinders 10, 12 and the last cylinder (not shown), thereby permitting firing to take place in the relatively unchilled cylinders 11, 13 and 14. This may be reversed, of course, by closing 45 supply valve 56 and leaving supply valve 59 open.

Where it is desired to rely entirely upon electrical starting equipment, or where an adequate supply of fluid under pressure, such as compressed air, is not available, the air starting units 50 may be removed by removing the crankcase cover plates and the one-way valves 98 and 129 in the cylinder heads. Replacing the one-way valves with plugs (not shown) and the covers 26, 27 and 28 with the usual blank cover plates 55 (not shown), conditions the engine for further operation. It will be noted that the application to or removal of these starting units from an engine does not materially alter or affect the engine organization, the only difference being that 60 with the air start units assembled to the engine, the engine will be conditioned for air starting, and with these units removed, the engine will have to be started by some other means, such as an electric starter.

65 It is to be understood that the present drawings and description thereof relate only to one embodiment of the invention, and that alterations and modifications in the structure and arrangement of the air start units may be made within the 70 spirit and intended scope of the invention, as defined by the appended claims.

75 1. In an air start system for an internal combustion engine, a pair of trunk conduits of sectional construction, each arranged along the engine to an extent to serve the air start cylinders

thereof, a valve for each of said conduits controlling the admission of air thereto, an air distribution valve for each cylinder, connected thereto and supplied from one of said conduits, each of said conduits including means for interconnecting the sections thereof, in straight or crossed relation whereby, through the addition or removal of sections the sectional conduit structure is adapted for application to engines of different number of cylinders and different firing order, each of said conduit sections being of an extent to serve a pair of adjacent engine cylinders and being provided with air distribution valve connections such that said valves of adjacent cylinders are connected to different conduit portions. 5

2. An air start system for internal combustion engines including an air supply manifold structure adapted to be mounted laterally of and upon the engine and including a plurality of sections adapted when connected in assembly, to serve as air trunk lines, each said section being of an extent to serve a pair of physically adjacent engine cylinders and each section providing a pair of parallel but separate air passages, a connection between a pair of said sections connecting the corresponding passages thereof to each other, another connection between adjacent sections serving to cross-connect the corresponding passages of the sections related by it, a plurality of air distribution valves and connections therefrom to the cylinders, and means connecting the air distribution valves of physically adjacent cylinders to different passages of the manifold section by which they are supplied. 20

3. In an air start system for multi-cylinder internal combustion engines, an air distribution valve for each cylinder to be subjected to air starting impulses, a manifold structure for starting air, including a plurality of sections each of an extent to supply the distribution valves of a plurality of adjacent cylinders, each such section being formed to provide a plurality of independent air conduits, means for selectively interconnecting the sections, together with valve means common to the sections whereby either conduit of a given section may be supplied with air while excluding air from the other conduit portion of the section, and means connecting the distribution valves of the separate cylinders served by a given section, each to a different conduit portion of the section. 30

4. In combination with a plural cylinder, internal combustion engine including a cam shaft driven thereby, a removable plate forming a 40 closure for an access opening to said cam shaft, said plate having a pair of conduits carried thereby adapted to receive air under pressure for starting the engine, valve means for effecting the selective control of air supplied to said conduits, a pipe connecting one of said conduits to one of the cylinders, a second pipe connecting the other conduit to an adjacent cylinder, a valve associated with each of said pipes for controlling the flow of air therethrough, and means connecting said last named valves for timed operation by said cam shaft. 45

5. In combination with a multi-cylinder internal combustion engine including a cam shaft driven thereby and a series of crank case openings, each of sufficient extent to provide access to the cams on said cam shaft identified with a pair of adjacent cylinders, removable closure plates for said openings, engine starting means of air pressure type associated with each closure 50 70 75

plate including two air supply conduits, a pipe connecting one of said conduits to one of the cylinders and a pipe connecting the other conduit to an adjacent cylinder, valves for controlling the flow of air through said pipes, means connecting said valves for timed actuation by the cam shaft, and pipe fittings interconnecting the supply conduits of the separate closure plates.

6. In combination with a multi-cylinder, internal combustion engine including a cam shaft driven thereby and a crank case having a series of openings, each confronting the cams on said cam shaft identified with a pair of adjacent cylinders, a removable closure plate for each crank case opening, means on each closure plate forming a pair of longitudinally extending conduits for

starting air, a pair of distribution pipes associated with each closure plate, connecting the cylinders identified therewith to said conduits, a valve in each distribution pipe, means connecting said valves for timed actuation by said cam shaft, pipe fittings interconnecting the conduits of adjacent closure plates in straight or crossed relation whereby to associate the cylinders into two groups, each adapted to receive starting air from one of the composite conduits, so that the cylinders making up each group are distributed with respect to the normal firing order of the engine, and valves for selectively controlling the admission of starting air to the composite conduits.

HUGO F. BUDZIEN.
